DESIGN FOR A FLEXIBLE POCKET RECEP- TACLE

Warner R. Buxton, Longmeadow, Mass.

Application December 21, 1937, Serial No. 73,777

Term of patent 14 years

To all whom it may concern:

Be it known that I, Warner R. Buxton, a citizen of the United States, residing at Longmeadow, in the county of Hampden and State of Massachusetts, have invented a new, original, and ornamental Design for Flexible Pocket Receptacles, of which the following is a specification, reference being had to the accompanying drawing, forming part thereof.

Fig. 1 is a top plan view; and

Fig. 2 is a face view showing the front face of

a flexible pocket receptacle embodying my new design.

The design appears wholly on the front face of the flexible pocket receptacle as shown in Fig. 2.

The lining on the drawing indicates contrasting surface appearance.

I claim:

The ornamental design for a flexible pocket receptacle substantially as shown and described.

WARNER R. BUXTON.
